UNITED STATES PATENT OFFICE

HARRY SCHWARTZMAN, OF JERSEY CITY, NEW JERSEY.

GARMENT-DISPLAY HOLDER.

Application filed September 8, 1928. Serial No. 304,695.

This invention relates to improvements in garment display holders and has particular reference to a holder for attachment to the back of a dress or the like for shaping the same when hung upon a garment hanger for display purposes for bringing out the stylish lines of the garment.

It has been the practice heretofore to take in the waist line of a dress to cause the same to hang properly while on display by folding the sides of the garment rearwardly and holding them in such position by a short length of thread or cord, but this means requires the passing of a needle through the material and if the dress is a delicate one, the same may prove damaging. Furthermore, this practice requires time and labor to apply the tie thread or cord and to cut the same when the dress is sold to a customer. It is therefore the primary object of this invention to provide a holder which may be quickly applied and removed from a dress without injuring the material, and which may be taken from one garment and used on another.

Another object of the invention is the provision of a garment holder which is simple in construction, and inexpensive of manufacture as it includes but a single length of elastic with snap hooks on opposite ends thereof.

With these and other objects in view, the invention resides in certain novel construction and combination and arrangement of parts, the essential features of which are hereinafter fully described, are particularly pointed out in the appended claim, and are illustrated in the accompanying drawing, in which:—

Figure 1 is a rear elevation of a lady's dress showing my holder device thereon.

Figure 2 is an enlarged horizontal sectional view therethrough on the line 2—2 of Figure 1.

Figure 3 is a perspective view of the holder per se.

Referring to the drawing by reference characters, the numeral 10 designates my improved holder device in its entirety which includes a single length of elastic cord 11, webbing or the like, to the opposite ends of which I connect fastening elements 12. Both of the elements 12 are of identical construction so that a description of one will suffice for the other.

Each fastening element 12 comprises a single piece of flat resilient metal bent between

its ends to provide an attaching eye 13 while one of its extremities is bent into a hook 14, the bill of which terminates in an out-turned lip 15. The other extremity constitutes a spring tongue 16, the outward flexing of which is limited by reason of the end of the same striking the bill of the hook. The spring tongue normally closes the open mouth of the hook but the same may be manually depressed to admit the part to be held thereby.

The fastening elements 12 are attached to the ends of the elastic by looping the same through the attaching eyes 13 and tying the same.

In use, the holder is applied to the back of a dress as shown in Figure 1 of the drawing, and is attached thereto by folding the sides of the dress rearwardly approximately at the waist-line which reduces the width of the garment when looking from the front and which imparts a natural hang to the garment to effectively set off the stylish lines. The fastening elements 12 are engaged to the edges of the backward folded portions with the elastic 11 bridging the space therebetween. The rounded lips 15 prevent possible cutting or marring of the dress material which is clamped thereagainst by the spring tongue 16. The elastic will adapt itself to the size of the garment and permit of the natural hang of the same. The device will be found most useful in ladies' dress shops and wherever dresses are hung for display purposes, as the same will not injure the dress such as caused by the present practice of passing pins and needles therethrough to produce a like effect.

When a dress is tried on by a customer, the holder may be readily removed and replaced when necessary, or if the dress is sold the holder may be used upon other garments. This attachment and removal of the holder may be quickly effected without the labor and expense heretofore resorted to.

While I have described what I deem to be the most desirable embodiment of my invention, it is obvious that many of the details may be varied without in any way departing from the spirit of my invention, and I therefore do not limit myself to the exact details of construction herein set forth nor to anything less than the whole of my invention limited only by the appended claim.

What is claimed as new is:—
A garment display holder comprising an

elastic element having its ends secured in looped formation, a snap hook for each end loop of said flexible element for detachable connection with the sides of a garment for taking in the width thereof, each snap hook including an attaching eye detachably receiving its looped end, said eye being restrict-

ed to prevent casual removal of the looped end therefrom, a hook portion having a rounded bill and a locking tongue normally engageable with said bill.

In testimony whereof I have affixed my signature.

HARRY SCHWARTZMAN.
